UNITED STATES PATENT OFFICE

111,060

DESIGN FOR A POWDER PUFF OR SIMILAR ARTICLE

Alice Bernstein, New York, N. Y.

Application June 14, 1938, Serial No. 77,826

Term of patent 3½ years

To all whom it may concern:

Be it known that I, Alice Bernstein, a citizen of the United States of America, residing in New York city, Borough of Bronx, county of Bronx, and State of New York, have invented a new, original, and ornamental Design for a Powder Puff or Similar Article, of which the following is a specification, reference being had to the accompanying drawing, forming part thereof, wherein,

Figure 1 is a plan view of a powder puff or similar article showing my new design.

The characteristic features of my design reside in the powder puff shown having combined therewith a pocket and a flap therefor of the specific configuration and arrangement shown.

I claim:

The ornamental design for a powder puff or similar article, substantially as shown and described.

ALICE BERNSTEIN.
